UNITED STATES PATENT OFFICE.

ROBERT H. VAN SANT, OF CHICAGO, ILLINOIS, ASSIGNOR TO VAN ESS LABORATORIES, INC., A CORPORATION OF DELAWARE.

REINFORCED APPLICATOR CAP.

Application filed January 23, 1925. Serial No. 4,137.

This invention relates to an improvement in applicators for massaging purposes. These applicators are generally made of rubber or the like and are adapted to fit upon an ointment bottle when in use. The applicator is usually provided with ointment feeding teats having ducts leading therethrough. During the operation of the applicator, these ducts sometimes became partially closed or clogged through the flexing of the rubber. To overcome this objection, it has been proposed to enlarge the outer and inner portions of the ducts in the ointment feeding teats. While this structure greatly overcame the previous objection, the manufacturing process thereof was somewhat difficult and expensive. In practice it has been found that these rubber applicators bulge upwardly and the teats bulge outwardly more or less, due to the expansion caused by the ointment. This bulging tends to restrict the flow of ointment through the teats.

The problem herewith concerned seeks to overcome this objection in the provision of an applicator that resists the outward bulging effect of the ointment feeding teats, that always maintains a sufficient flow of ointment and that can be economically manufactured.

The invention comprises the novel structure and combinations hereinafter described and more particularly pointed out and defined in the appended claim.

In the accompanying drawings which illustrate a preferred form of this invention and in which similar reference numerals refer to similar features in the different views:

Figure 1 is an elevational view of an ointment bottle equipped with an applicator involving this invention.

Figure 2 is a sectional view upon the line II-II of Figure 3.

Figure 3 is an enlarged vertical sectional view of the applicator showing a fragment of the ointment bottle attached thereto.

Figure 4 is a view similar to Figure 3 illustrating the form of the applicator after acted upon by the ointment.

As shown on the drawings:

The applicator comprises a rubber disk 1

that is attached to the top of the ointment bottle by means of a screw threaded metal member 2, the upper portion of which engages over the outer margin of the disk.

This disk is provided with an outer circular series of massaging nipples 3 and a plurality of shorter ointment feeding teats or nipples 4, having suitable ducts 5 extending therethrough and through the base of the applicators. These ducts are of uniform bore and of sufficient size to prevent the same from closing or restricting the flow of ointment on account of the flexure arising from the operation of the applicator.

A metal plate 6 is embedded in the base of the applicator and is provided with small apertures 7 coaxially with the ducts 5. This plate member will reinforce the rubber disk and prevent the outward bulging of the ointment feeding teats 4; at the same time the smaller apertures in the plate 6 will restrict the flow of ointment to the desired amount. There will, however, be an upward bulging of the top of the disk as shown in Figure 4; the flexure occurring between the margin of the plate 6 and the attaching flange of the disk, whereby the massaging nipples will bulge outwardly bringing their tops nearer to the tops of the teats 4 which will remain vertical. In other words, the portion of the disk containing the plate 6 will be elevated in a straight horizontal plane.

The lower surface of the disk is provided with the rib 8 that is adapted to expand against the neck of the bottle, and a circular expansion groove 9 concentric of said rib and located within the confines thereof.

It will be appreciated that the large uniform bores in the ointment feeding nipples or teats simplifies the manufacture thereof, and the embedded reinforcing plate 6 not only restricts the flow of ointment that would naturally flow through the ducts; it also resists the outward bulging of the ointment feeding nipples and prevents the ducts therein from partially closing so that the steady desired flow of ointment is secured.

I am aware that many changes may be made, and numerous details of construction may be varied through a wide range without

departing from the principles of this invention, and I therefore do not purpose limiting the patent granted hereon, otherwise than necessitated by the prior art.

5 I claim as my invention:

An applicator, comprising a flexible disk having ointment feeding nipples with en-

larged uniform bores, and a metal plate embedded in and surrounded by the material of said disk and having smaller apertures than ¹⁰ said bores in registry therewith.

In testimony whereof I have hereunto subscribed my name.

ROBERT H. VAN SANT.
